United States Patent Office

Des. 175,982
Patented Nov. 1, 1955

175,982

STEAM TRAVEL IRON

William J. Russell, New Britain, Conn., assignor to Landers, Frary & Clark, New Britain, Conn., a corporation of Connecticut

Application August 26, 1954, Serial No. 32,037

Term of patent 14 years

(Cl. D49—6)

FIG.1

FIG.2

FIG.3

FIG.4

FIG.5

Figure 1 is a perspective view of a steam travel iron showing my new design;

Figure 2 is a front view thereof on a reduced scale;

Figure 3 is a rear view thereof on a reduced scale;

Figure 4 is a perspective view of the steam travel iron with its handle folded for traveling;

Figure 5 is a front view, on a reduced scale, of the iron shown in Figure 4; and

Figure 6 is a rear view on a reduced scale, of the iron shown in Figure 4.

FIG.6

I claim:

The ornamental design for a steam travel iron, as shown.
